UNITED STATES PATENT OFFICE

166,600

COMBINED PLATE AND ATTACHING CLAMP

Dorothy W. Fry, Norristown, Pa.

Application April 7, 1950, Serial No. 9,038

Term of patent 14 years

(Cl. D44—29)

To all whom it may concern:

Be it known that I, Dorothy W. Fry, a citizen of the United States, residing at Norristown, Pennsylvania, have invented a new, original, and ornamental Design for a Combined Plate and Attaching Clamp, reference being had to the accompanying drawing, forming part thereof.

In the drawing—

Fig. 1 is a top plan view of a combined plate and attaching clamp showing my new design;

Fig. 2 is a side view thereof; and

Fig. 3 is a bottom plan view thereof.

The dominant features of the design reside in the portion drawn in full lines comprising a clamp of generally curved configuration attached to the upper rim of a plate at one end

and terminating in a horizontally disposed disc or clamp jaw at its other end, as shown.

I claim:

The ornamental design for a combined plate and attaching clamp, as shown and described.

DOROTHY W. FRY.
